CONTAINER

Robert E. Read, Watertown, N. Y.

Application July 6, 1934, Serial No. 733,947
Renewed May 21, 1937

7 Claims. (Cl. 229—29)

My present invention relates to improvements in carriers or containers for fragile and breakable articles, and more particularly, to improvements in carriers or containers for eggs or like articles so designed as to prevent breakage of the packed articles during shipment and which will, at the same time, provide a suitable and convenient means for dispensing the articles in retail quantities.

10 Although many carriers or containers for eggs and other fragile articles have been developed their use has not become widespread due primarily to the fact that they are designed either for handling such articles during shipment or for handling such articles in retail quantities. No container, of which I am aware, has been developed which meets the needs of the shipper and which will, at the same time, fulfil all of the requirements of the retail trade. Heretofore, it

15 has been considered impossible to construct such a container which will embody features satisfying the requirements of the packer and the retailer. As far as I am aware, these features of construction have been considered to be mutually exclusive in nature and could not be embodied in a single container. I have found, however, that the construction of a container satisfactory both to the wholesale and the retail trade is not impossible.

20 Accordingly, it is an object of my present invention to provide a container for eggs and other fragile and breakable articles, made preferably of moulded pulp material, which is rigid in construction, compact in size and which serves as a

25 protection for the packed articles when the container is subjected to the various shocks and strains incident to shipping and handling.

Another object of my present invention is to provide a carrier or container for eggs and the like which is provided with one or more rows of receiving cells, each row of cells being provided with a rib formed by impressing a suitably shaped channel in the material from which the carrier or container is formed. Each rib extends

30 across a row of cells and is so shaped as to hold the container against distortion and, at the same time, to serve as means for cushioning the packed articles against any shocks or strains to which they might possibly be subjected either during

35 shipment or in the retail establishment.

Still another object of my present invention is to provide a carrier or container for eggs and the like which is provided with one or more rows of article receiving cells, each row being provided with a rib formed by impressing a suitably shaped channel in the material from which the carrier or container is formed. Each rib extends across a row of cells and is provided with a concave top joining the side walls. By this construction the

40 container is held against distortion and any-

5 shocks are transmitted through the rib to the walls of the container and are not transmitted directly through the packed articles.

Still another object of my invention is to provide a carrier or container for eggs having a plurality of egg receiving cells, the said cells being reinforced by suitably shaped ribs. The egg cells are formed so as to maintain the eggs in upright position thereby reducing the size of the container so that it may fit within standard sized sleeves, now in general use and thereby permitting a plurality of said containers to be packed in standard shipping cases.

Still another object of my present invention is to provide a carrier or container for eggs and like fragile objects having a plurality of article receiving cells so designed as to maintain the contained objects in upright position and at the same time to cushion the ends of such objects. The carrier or container comprises complementary sections or portions, each section or portion being provided with cells of the aforesaid design. The sections are hinged together by means so designed as to prevent the rubbing or crushing of the contained objects in the lower section as the upper section is being folded over the lower section into closed position.

A further object of my present invention is to provide a carrier or container for eggs and the like which is provided with one or more rows of egg receiving cells, each row being provided with a rib designed to hold the container against distortion and, at the same time, to provide a cushioning means for the packed articles. The container is also provided with one or more transverse ribs which serve to prevent lateral expansion of the ribs running across the rows of cells and hence serve further to strengthen the container.

These and other objects of my present invention will become more apparent from a study of the following description considered in connection with the attached drawings in which:

Fig. 1 is a top plan view of one form of my invention;

Fig. 2 is an end elevation thereof;

Fig. 3 is a sectional view taken along the lines 3—3 of Fig. 2;

Fig. 4 is a sectional view taken along the lines 4—4 of Fig. 2;

Fig. 5 is a longitudinal sectional view taken along the lines 5—5 of Fig. 1;

Fig. 6 is a longitudinal sectional view taken along the lines 6—6 of Fig. 1;

Fig. 7 is a perspective view of one form of my invention;

Fig. 8 is a top plan view of a modification of my invention showing the container in opened position;

Fig. 9 is a top plan view of the modification

shown in Fig. 8 with the container in closed position;

Fig. 10 is a sectional view taken along the lines 10—10 of Fig. 9; and

5 Fig. 11 is a sectional view taken along the line 11—11 of Fig. 10.

Referring now more particularly to the drawings in which like numerals indicate like parts I have shown in Figs. 1 to 7, inclusive a preferred 10 form of my invention. In these views the carrier or container A, formed preferably of moulded pulp material, is shown as comprising a lower section or half 20, hingedly secured by means of a connecting strip 21 to the upper section or half 15 22. Although any suitable method may be used in forming the carrier or container from the pulp material I prefer to use a suction moulding process wherein the pulp is forced against a foraminous mould of the desired configuration by the 20 application of suction on the inner face of the mould. However, it is to be understood that other moulding processes may be used to form my improved contained without limiting in any way the scope of my invention.

25 Each portion or section is provided with a plurality of article receiving cells 23 projecting from the face of the sheet 24. These cells are arranged in parallel rows and although the number of cells and rows may vary each section consists 30 preferably of a dozen cells arranged in two parallel rows of six cells each. The faces of these sheets 24 of both the upper and lower sections are adapted to abut each other in a manner to be hereinafter more particularly described whereby 35 the aligned cells of such upper and lower sections form individual article receiving cells.

In the forms of containers now in use it has been found that they do not afford sufficient protection to the articles packed in the container 40 in that the container is liable to become bent or distorted, frequently resulting in breakage to the articles packed therein. In order to eliminate this and other faults I have provided each row of cells with a rib 25 extending substantially 45 continuously along each row. These ribs retain the container against longitudinal bending. Each of the ribs 25 is substantially trapezoidal in cross section, being provided at its top with a concave surface 26 which serves to cushion the 50 ends of the articles packed in the cells. The top of each rib should lie at least in the same plane as the base of the cells in each section or half 20 and 22. Preferably, however, the top edges of these ribs extend slightly above the base of the 55 cells so as not only to increase the strength of the ribs but also to provide additional protection for the ends of the articles packed in the cells.

As will be noted from an inspection of Fig. 1, each of the longitudinally extending ribs is broken 60 by the transverse ribs 27 which intersect the longitudinal ribs at spaced intervals. The tops of these transverse ribs lie in a plane below the tops of the longitudinally extending ribs and divide each longitudinal rib into three sections. The top 65 28 of each transverse rib is also substantially narrower than the top of each longitudinal rib thereby affording greater rigidity to the transversely extending ribs. By the construction above described the transverse ribs prevent lateral expansion 70 of the container and do not interfere in any substantial degree with the functioning of the longitudinally extending ribs. In addition, ribs 29 may be provided which serve to tie the inner walls 30 of the longitudinally extending ribs 75 together. These ribs also serve an additional

function in protecting the contained articles against damage in a manner to be hereinafter more particularly described.

As has been hereinbefore stated, the sections 20 and 22 are hinged together by a strip 21. This strip forming the hinge of the container comprises a central member defined by two parallel weakened portions or score lines 31 and 32 formed during the moulding operation by means of suitably formed projections on the mould. In practice, these projections comprise wires which decrease the thickness of the material along the lines indicated. The construction of this hinge is extremely important when it is desired to provide a suitable container for retail use. By providing a hinge of substantial width the upper section or portion may be folded over on top of the lower section or portion without disturbing the objects standing on end in the cells. Since the container is designed primarily to handle 20 eggs it would be impossible to provide a container having a hinged cover in which container the eggs are stood on end. In other containers of this general type the eggs must of necessity be placed on their sides necessitating the use of an 25 odd sized shipping container or crate. Since, in the shipping and handling of eggs, the shipping container or crate has long since been standardized the difficulties incident to side packing of eggs have been heretofore insurmountable. By 30 the hinge construction described above sufficient room is allowed to permit the upper section or portion 20 to be folded over on the lower section or portion 22 without rubbing against the eggs or crushing them. Further, by the packing of 35 eggs on end, the eggs are so positioned as to withstand the shocks to which the eggs are subjected during shipment. As is well known, an egg is stronger along its greater diameter than along its shorter diameter.

40 Referring now specifically to Fig. 7, it will be noted that by the provision of the article receiving cells 23 the ribs 25 and the tie ribs 29, the interior of the container comprises a plurality of partitions 33 having concave walls merging 45 into the bottom of the cells. These partitions are formed or defined by depressions 34 and 35 located between alternate cells in each row, the depressions 34 constituting the inner walls of the transverse ribs 27, and the depressions 35 constituting the inner walls of the tie ribs 29. By 50 this construction each article receiving cell is shaped to hold the contained article and contact between articles in adjacent cells of each row is prevented.

55 The container is also provided with a plurality of dividers 36 serving to separate the inner row of cells so as to prevent contact between articles in adjacent cells. These dividers are located adjacent the hinge strip 21 and, as will be noted 60 from an inspection of Figs. 3 and 4, do not interfere with the hinge action of the hinge strip but, on the contrary, serve to accentuate the hinge construction. Thus, in Fig. 3 the hinge 65 is shown in closed position with the top of the dividers 36 of the upper and lower container halves abutting each other. Hence, these dividers serve to prevent the hinge from being broken and thereby prevent the crushing of the contained articles when the top half is moved to closed position. Any shock adjacent the hinge will not be transmitted through the contained articles but through the material of the container. This feature is of extreme importance 70 75

since during shipment the likelihood of breakage is minimized.

Referring now to the modification disclosed in Figs. 8 to 11 inclusive. It will be seen that I have provided a carrier or container of the same general construction and form to that disclosed in Figs. 1 to 7 inclusive. However, in the modified form the continuity of the longitudinally disposed ribs 25' is unbroken throughout the length of the ribs. A plurality of tie ribs 29' are provided to strengthen the container across its shorter diameter. Each longitudinally disposed rib 25' is provided with a concave upper surface 28' and is substantially similar in construction to the longitudinal ribs disclosed in Figs. 1 to 7 inclusive with the exception that the top edges 31 of each rib is rounded thereby affording a more resilient cushioning means for the contained articles.

The interior of the container is identical in form and construction to the interior of the container disclosed in Figs. 1 to 7 inclusive, the central dividers 33' being formed however by the depressions 34' constituting the inner walls of the tie ribs 29'. As in the modification disclosed in Figs. 1 to 7 inclusive dividing means 36' are provided adjacent the hinge strip 21'.

It will be appreciated by those skilled in the art that other modifications may be provided without departing from the spirit or scope of my invention. Thus, the container may be provided with transverse ribs adjacent either end of the container or the tie ribs may be dispensed with entirely or supplanted with transverse ribs cutting through the longitudinal ribs.

From the above description it will be appreciated that my container provides a simple and inexpensive means for the packing, shipping and selling of eggs. This latter feature of my invention is further emphasized when it is considered that the container is of such form that it may be placed within an outer sleeve of standard form such as is readily available in the market. This type of container can be made for even less cost than any of the containers now on the market and add in a marked degree to the security of the articles packed therein. Although I have shown and described the preferred embodiment of my invention it is to be understood that I can make many changes and alterations in the specific construction without departing from the spirit of my invention as set forth in the appended claims.

I claim:

1. A fragile article container of the character described comprising in combination, a member formed with a row of cavities to provide a row of article receiving cells, a reinforcing rib extending through said row of cells and forming webs between adjacent cells, the top of said rib being substantially concave throughout its length, a rib extending transversely across said container and through said first mentioned rib, said transversely extending rib cutting through said reinforcing rib, the top thereof being in a plane below the plane of said reinforcing rib whereby to impart rigidity to said container across its shorter diameter.

2. An article container of the character described comprising a member formed with rows of cavities to provide rows of article receiving cells, a reinforcing rib extending through each of

said rows of cells and forming webs between adjacent cells in each row, the top of each of said ribs being substantially concave throughout its length, ribs extending transversely across said container and through said reinforcing ribs, said transversely extending ribs cutting through said reinforcing ribs, the tops thereof being in a plane below the plane of said reinforcing ribs whereby to impart rigidity to said container across its shorter diameter.

3. An article container of the character described comprising a member formed with rows of cavities to provide rows of article receiving cells, a reinforcing rib extending through each of said rows of cells and forming webs between adjacent cells in each row, and ribs connecting adjacent rows of cells and located between these cells and merging with the webs formed by the reinforcing ribs extending through each row.

4. An article container of the character described comprising a member formed with rows of cavities to provide rows of article receiving cells, a reinforcing rib extending through each of said rows of cells and forming webs between adjacent cells, the top of each of said ribs being substantially concave, ribs extending transversely across said container and cutting through said reinforcing ribs, the tops of said transverse ribs being in a plane below the plane of said reinforcing ribs, tie ribs connecting adjacent rows of cells and merging with the webs formed by the reinforcing ribs extending through each row of cells.

5. A container of the character described comprising sheets of moulded material provided with article holding cups, the sheets forming by means of said cups rows of article receiving cells, a strip of moulded material formed integrally with said sheets to provide a hinged connection therebetween, means adjacent the margins of said strip and merging into said margins adapted to abut each other when said sheets are in superimposed relation whereby to transmit any vertical force away from articles in said cells and away from said strip.

6. A container of the character described comprising sheets of moulded material provided with article holding cups, the sheets forming by means of said cups rows of article receiving cells, a strip of material formed integrally with said sheets to provide a hinged connection therebetween, each sheet having a raised portion adjacent one side of said strip and merging into said hinged connection, said raised portions when said sheets are in superimposed relation abutting one against the other whereby to transmit any vertical force away from articles in said cells and said strip, said hinged connection being defined by parallel weakened lines.

7. A container of the character described comprising sheets of moulded material provided with article holding cups, the sheets forming by means of said cups article receiving cells, a strip of moulded pulp material lying in a single plane and formed integrally with said sheets to provide a hinged connection therebetween, a series of members formed in each sheet adjacent its edge of said strip and merging into said edge, the members of each sheet being adapted, when said sheets are in superimposed relation to abut against the members of the opposite sheet whereby to transmit vertical loading without effect on said strip.
